UNITED STATES PATENT OFFICE.

MARTIN L. HECKERT, OF MOUNT CARMEL, PENNSYLVANIA.

NON-GLARING HEADLIGHT.

1,199,071.

Specification of Letters Patent. Patented Sept. 26, 1916.

Application filed November 19, 1915. Serial No. 62,335.

To all whom it may concern:

Be it known that I, MARTIN L. HECKERT, a citizen of the United States, residing at Mount Carmel, in the county of Northumberland and State of Pennsylvania, have invented certain new and useful Improvements in Non-Glaring Headlights, of which the following is a specification.

This invention relates to headlights such 10 as are used on automobiles, suburban cars, and other vehicles.

Such headlights, as usually constructed, are provided with reflectors which project a powerful beam of light so directed as to 15 shine full in the eyes of persons moving in the opposite direction. This glare produces blinding and highly disagreeable effects, and while many attempts have been made to 20 overcome this objection by the use of dimmers of various kinds, such attempts have frequently resulted in cutting off the light to such an extent that the roadway over which the vehicle is traveling is not properly illuminated. The glare above referred 25 to is due largely to the fact that the reflectors employed are so shaped as to throw the light upwardly as well as downwardly.

It is the object of the present invention to 30 limit the field of illumination without reducing its intensity, and to confine all of the reflected rays to an area below the axis of the reflector. This is accomplished by so shaping the upper part of the reflector that all rays impinging thereon will be thrown 35 downwardly across the said axis. In this way, the field in close proximity to the lamp is brilliantly lighted, but the major portion of the light rays are so inclined as to strike the ground a short distance away. The 40 lower part of the reflector is also preferably so shaped that the light therefrom is thrown more directly downward than is the case with the parabolic reflectors now in use.

In order that the invention may be readily 45 understood, I have illustrated one embodiment thereof in the accompanying drawings, in which,

Figure 1 is a central vertical section 50 through my improved reflector; and, Fig 2 is a front view thereof.

Referring to the drawings in detail, my improved headlight preferably consists of the usual casing 1, in which is mounted the reflector 2. These parts are secured together 55 by a sheet metal ring 3, in any suitable manner, and in front of the reflector is located

a protecting glass 4, mounted in a suitable ring 5.

6 designates the source of light, which may be an electric, or any desired type of 60 lamp.

My improved reflector consists of a relatively small parabolic central portion 7, which is symmetrical about the axis $x-x$, and in the focus of which the lamp 6 is preferably located. The result of this is that 65 the parabolic portion 7 of the reflector projects a concentrated beam of substantially parallel rays, as indicated at 8.

As above mentioned, the part of the reflector above the parabolic portion 7 is so shaped as to throw the light rays downwardly. In the embodiment shown in the drawing, this is accomplished by providing a series of arc-shaped concentric reflecting 75 bands or strips 9, separated by other bands or strips 9^a, which are so disposed as not to be directly illuminated by the lamp.

By reference to Fig. 1, it will be seen that 80 the bands or surfaces 9 are disposed at progressively varying angles to the axis $x-x$, the angle becoming more and more acute as the distance from the axis increases. This has the effect of causing the rays passing radially out from the lamp and impinging 85 upon these surfaces to be reflected downwardly across the axis as a somewhat diffused but substantially parallel beam. The direction of the reflected rays is indicated at 10 in Fig. 1.

The lower part 11 of the reflector below 90 the parabolic portion 7 is preferably flared to a greater extent than in the usual reflector, with the result that the reflected rays are given a decidedly downwardly inclined 95 direction, as indicated at 12, in Fig. 1.

It will thus be seen that the reflected rays 100 from both the upper and lower portions of the reflector are projected at an angle to the axis $x-x$ and in the same general downward direction, while a small central concentrated beam is thrown by the parabolic portion of the reflector in a direction parallel with such axis. Assuming the axis to be horizontal, it is therefore obvious that 105 the main volume of light strikes the ground within a short distance in front of the reflector, while at greater distances, none of the light rays extend above the level of the source of light. If, therefore, the headlights are placed at the usual height, the 110 rays are thus prevented from being thrown

into the eyes of pedestrians and drivers of approaching vehicles.

What I claim is:

1. A reflector for headlights having a parabolic center shaped to throw a horizontal beam, a source of light in the focus thereof, and an upper portion and a lower portion surrounding said center and both shaped to reflect the rays downwardly at an angle to the axis of the parabola.

2. A headlight reflector of circular shape and a source of light at the center thereof, the portion of the reflector above the said light being formed of a series of arc-shaped concentric reflecting bands arranged at angles to each other and so disposed as to direct the rays downwardly.

3. A headlight reflector of parabolic shape, and a source of light in the focus thereof, a portion of the inner surface of the reflector above the light being formed

of a series of arc-shaped concentric reflecting bands disposed at progressively varying angles to the axis of the reflector, and so arranged as to direct the rays downwardly. 25

4. In a headlight, the combination with a reflector having, in general, a parabolic shape, of a source of light in the focus thereof, the central portion of such reflector being a substantially true paraboloid designed to project a beam of parallel rays, the upper portion of said reflector comprising angularly disposed reflecting bands, and the lower portion having a smooth surface designed to reflect the light rays downwardly. 30 35

In testimony whereof I affix my signature in presence of two witnesses.

MARTIN L. HECKERT.
